UNITED STATES PATENT OFFICE.

CARL STÜRMANN AND ALEXANDER MOLL, OF DUSSELDORF, GERMANY.

SLIDING WINDOW.

1,002,777.

Specification of Letters Patent.

Patented Sept. 5, 1911.

Application filed February 17, 1911. Serial No. 609,174.

To all whom it may concern:

Be it known that we, CARL STÜRMANN and ALEXANDER MOLL, subjects of the German Emperor, and residing at 23 Bilkerstrasse, Dusseldorf, and 23 Immermannstrasse, Dusseldorf, Germany, respectively, have invented certain new and useful Improvements in Sliding Windows, of which the following is a specification.

- 10 The present invention relates to a sliding window, the sashes of which are moved by means of metallic guide straps into their upper and lower position respectively and which may for cleaning purposes be swung 15 toward the inside of the room, and the guide and hinge members of which are made of metal independently of the wood work of the window, so that the window can be quickly and easily constructed.
- 20 The invention consists in that the side-bars of the window are fitted with metallic guide bars, of which those on one side of the window are adjustable in the respective side-bars, and admit of the sashes swinging 25 around the other guide bars toward the inside of the room, after they have been disconnected from the adjustable guide-bars.

The invention furthermore consists in certain constructional details, which relate 30 to the combined guide and hinge straps as shall be hereinafter more fully described and be specified in the claims.

In the accompanying drawing Figure 1 is a front view of the improved window, the 35 two sashes of which can slide in a vertical direction and swing toward the inside of the room. Fig. 2 is a vertical longitudinal section through the window along the line A—B in Fig. 1. Fig. 3 is a transverse section 40 along the line C—D in Fig. 1 when both sashes are lowered. Fig. 4 is a similar section with the guide and sashes straps of a somewhat modified form. Fig. 5 is a vertical longitudinal section along the line 45 E—F in Fig. 3 and Fig. 6 is a vertical longitudinal section along the line G—H in Fig. 5.

Similar letters of reference indicate the same parts in the different figures of the drawings.

As shown in the drawings the upper sash *a* and the lower sash *b* of the window are both guided in the window frame *c*, which

is provided on one side with boxes *d* closable by a front strip, in which the balance 55 weights *e* move. The latter are connected to the sides of the sashes by means of cords *f* running over rollers provided at the upper right hand corner of the window frame. On the sides of the weight boxes the window 60 frame consists of two side-bars *g*, each of which is intended to serve as a guide to one sash, and to the corners of which the combined guide and hinge members *h*, *i*, lying in different planes are connected, 65 which receive the hinge strap *k* secured to the side of the sash.

The guide member *h* consists of a metallic bar of angular section, with unequal sides, the longer side *h'* of which is secured to the 70 front of the posts *g* and the shorter side of which, *h''* terminates in a beaded enlargement *h''* of circular section and is turned toward the inside. The guide member *i* consists of a metallic bar with a center piece *i'* 75 of approximately the shape of a quadrant and side pieces *i''* and *i'''* vertically arranged to the said quadrant and extending therefrom in the form of flanges, of which the one flange *i''* enters into the center piece and is 80 secured to the inside of side-bar *g*, while the other flange *i'''* is secured to the point of the side-bar *g* and is in such a manner riveted to the side *h'* of the guide member *h*, that only a narrow gap equal to the thickness 85 of a hinge strap remains between its end toward the shorter side *h''* of the latter and the bead *h''* on the guide member *h*, and the center of curvature of the center piece *i'* of the bar *i* coincides with the center of the 90 bead *h''* of the guide bar *h*. The hinge-strap consists of a metallic bar of angular section with unequal sides, the longer side *k'* of which is secured to the side of the sash, whereas the shorter side *k''* which is guided 95 in the slot between the two guide bars *h*, *i* is bent close to its base toward the outside and thickened shortly before its end and bent inwardly in a circular curve, so that outer curve of the first bend *k''* fits like a 100 hinge on the bead *h''* of the guide bar *h* and the outer curve *k'* of the second bend has the same center of curvature as the first one and bears against the uniformly curved central part *i'* of the guide bar *i*. In consequence of such arrangement and construc- 105

tion of the guide bars h , i and the hinge straps k the sashes may not only be raised and lowered in the former, but also be swung around about a right angle toward the inside for cleaning purposes, when the guide bars on the other side of the sashes of the window have been disengaged. On the sashes being swung inwardly, the bands k^4 of straps k will strike against the inwardly projecting end of the flanges i^2 of the guide bar i and retain the sash, as is clearly shown in Fig. 3.

The guide bars, which are fitted to the sides of the sashes a , b opposite to the guide bars h , i consist of two flat iron straps l , m of which the upper one is rigidly, and the lower one adjustably held in longitudinal slots m^1 of the respective side-bar g . These guide bars project along their entire length from the side of the side-bars and engage with the projecting part in corresponding grooves m^2 in the sashes and give the latter together with the guide bars h , i on the opposite side the necessary guidance in the window frame and the necessary security against the sashes swinging accidentally out of the frame. For disengaging the guide bars m from the grooves m^2 in the sashes an ear m^3 has been riveted to the bars m at top and bottom and fitted with a pin m^4 , on which a nut n with a slotted hole n^1 engages, which nut n may be moved by means of a short shaft rotatably journaled in a recess in the respective side-bar g in an inside transverse bar o and in an outer sleeve o^1 , which shaft is for the said purpose carried through a slotted hole m^5 and terminates on the outside of the side-bar g in a square end, on which the corresponding socket of a handle p^1 or the like can be fitted. The short shaft p for the rail m of the upper sash is journaled below the shafts p for the rail m of the lower sash. The lugs n have extensions n^2 which strike against the stop pin n^3 of the transverse bars o , so as to limit thereby their stroke. When the sash is to swing toward the inside of the room, it must first be moved into its lowermost position, thereupon first the upper and then the lower part of its guide bar m or vice versa is moved by means of the handle p from the guide groove in the sash, so that now the latter may swing freely. When the sash is to be secured against swinging out its guide bar m need only be returned in the corresponding manner into the guide groove of the sash.

With the combined hinge and guide straps according to Fig. 4 the shorter side h^2 is of a plain semi-circular section and with its circular central part concentric to the same and the other guide bar i is secured with its one flange i^3 to the longer side h^1 of the rail, the guide slot for the hinge strap k being maintained, whereas the flange i^2 according

to the hereinbefore described constructional form is entirely dispensed with. The shorter side h^2 of the hinge strap has a corresponding semi-circular section and is provided at its end with a lug k^5 and guided between the side h^2 of the bar h and the side i^1 of the bar i . Otherwise the arrangement of the bars h , i is the same as in the construction shown in Figs. 1 to 3. When the sashes swing out the lugs k^5 strike against the end of the sides h^2 of bar h .

The improved window-sashes have the advantage that the so-called "hard-ware" required for the same can be supplied to window-sash factories and there made up into sashes in a quick and economical manner.

We claim:

1. In a sliding and turning window-sash, the combination, with the sash and side-bar of the window-frame, of a hinge-strap attached to the sash and formed of partly straight and partly curved portions, combined guide and hinge-bars secured in corresponding recesses of the side-bar, the front one of said guide and hinge-bars consisting of a metallic bar of angular cross-section and unequal sides, secured by its longer side to the front of the side-bar and terminating at its shorter side in a circular bead, and of a metallic rear-bar having a center portion in the form of a quadrant concentric with the bead on the front-bar and provided at each end of said quadrantal portion and at right angles thereto with flanges, of which one projects across said center portion and is attached to the side-bar of the window-frame, while the other is secured to the longer side of the front-guide bar, the front-edge of the side-flange forming with the bead of front guide-bar a narrow slot for guiding the sash hinge-strap.

2. In a sliding and turning window-sash, the combination, with the sash and side-bar of the window-frame, of a hinge-strap attached to the sash and formed of a metallic bar of unequal sides, the longer of which is attached to the side of the sash, and the shorter of which is bent up at one end into a straight portion at right angles to the longer side and into a thickened curved portion, combined guide and hinge-bars secured in corresponding recesses of the side-bar, the front one of said guide and hinge-bars consisting of a metallic bar of angular cross-section and unequal sides, secured by its longer side to the front of the side-bar and terminating at its shorter side in a circular bead, and of a metallic rear-bar having a center portion in the form of a quadrant concentric with the bead on the front-bar and provided at each end of said quadrantal portion and at right angles thereto with flanges, of which one projects across said center portion and is attached to the side-bar of the window-frame, while the other is

secured to the longer side of the front-guide bar, the front-edge of the side-flange forming with the bead of front guide-bar a narrow slot for guiding the sash hinge-strap, the curved portion of the sash hinge-strap being concentric with the bead of the front guide-strap and the quadrantal portion of the inner or rear guide-strap.

In testimony whereof we affix our signatures in presence of two witnesses.

CARL STÜRMANN. [L. S.]
ALEXANDER MOLL. [L. S.]
